UNITED STATES PATENT OFFICE.

GEORGE A. WIELAND AND WILLIAM F. ALDRICH, OF SAN FRANCISCO, CALIFORNIA.

WALL STRUCTURE.

1,073,829.

Specification of Letters Patent. Patented Sept. 23, 1913.

Application filed September 19, 1912. Serial No. 721,246.

To all whom it may concern:

Be it known that we, GEORGE A. WIELAND and WILLIAM F. ALDRICH, citizens of the United States, residing at San Francisco, in the county of San Francisco, State of California, have invented certain new and useful Improvements in Wall Structures; and we do hereby declare the following to be a full, clear, and exact description of the invention, such as will enable others skilled in the art to which it appertains to make and use the same.

This invention relates to wall supporting structures.

15 The object of the invention resides in the provision of a wall structure which will facilitate the construction of walls wherein there is employed composition plaster boards or the like.

20 A further object of the invention resides in the provision of a wall structure which includes an improved form of studding and plaster board fastening clip, the latter detachably interlocking with the studding and 25 adapted securely to hold the plaster boards in place.

With the above and other objects in view, the invention consists in the details of construction and in the arrangement and combination of parts to be hereinafter more fully described and particularly pointed out in the appended claim.

In describing the invention in detail, reference will be had to the accompanying drawings wherein like characters of reference denote corresponding parts in the several views, and in which—

Figure 1 is a side view of a section of a wall constructed in accordance with the invention, Fig. 2, a section on the line 2—2 of Fig. 1, Fig. 3, a section on the line 3—3 of Fig. 1, Fig. 4, a perspective view of a fragment of one of the studdings employed in the structure. Fig. 5, a detail perspective view of one of the board fastening clips with the tongue at the respective ends of the clip in the position they would occupy before being bent into securing relation to the plaster board, and Fig. 6, a detail perspective view of one of the board fastening clips with the tongues at the respective ends of the clip in the position they would occupy after being bent into fastening relation to the plaster boards.

55 Referring to the drawings a wall structure is shown as comprising a plurality of

vertical studdings A. Each of these studdings A are U-shape in cross section so as to form parallel spaced arms 10 and 11. Formed in the arms 10 and 11 at corresponding points and in vertical alinement are openings B and C respectively. The lower ends of each of the openings B and C are reduced as at 12 and 13 respectively for a purpose that will presently appear. The board securing clip of the structure is shown as comprising a plate D provided with a central offset portion 14 forming shoulders 15 and 16. The longitudinal edges of the offset portion of the fastening clip are provided respectively with laterally directed flanges 17 and 18 whereby said clip is strengthened. The ends of the fastening clip are slit longitudinally as at 19 so as to form tongues 20 and 21.

In constructing the wall through the medium of the studding and fastening clips heretofore described the studdings A are arranged on a suitable foundation in spaced relation to each other. The board fastening clips are then applied through alining openings B and C. In applying these fastening clips the offset portion 14 thereof can readily pass through the upper portion of the openings B and C, and when said offset portion is disposed between the arms 10 and 11. The ends of the fastening clips are brought into registration with the reduced portions 12 and 13 of the openings B and C and passed into said reduced portions. In this manner the fastening clips are locked against longitudinal movement by engagement of the shoulders 15 and 16 with the inner faces of respective arms 10 and 11. After the fastening clips have been applied in the various alining openings B and C the plaster boards E are arranged against the outer faces of the arms 10 and 11 so that the adjacent edges of said board are disposed relatively close to opposite sides of the slotted ends of the fastening clips when the tongues 20 and 21 of which said ends of the fastening clips are constituted, are bent in opposite directions across the outer faces of adjacent boards E and in this manner said boards are effectively secured to the studdings A.

What is claimed is;

In a wall structure, the combination of a plurality of studdings each of which is U-shape in cross section and has its arms provided with alining openings, the lower

portion of which latter are reduced in width, wall members having their adjacent ends disposed against the outer faces of the arms of the studdings, and wall member 5 fastening clips extending through alining openings in the arms of the studdings and having their intermediate portions offset to form shoulders adapted to engage the inner face of the arms of the studdings when the 10 terminals of said clips are disposed in the reduced lower ends of alining openings, the

terminals of said clips being slit longitudinally to form tongues and the latter being bent in opposite directions over adjacent ends of the wall members.

15

In testimony whereof, we affix our signatures, in presence of two witnesses.

GEORGE A. WIELAND.
WILLIAM F. ALDRICH.
